UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 14,032, dated July 3, 1883.

Application filed May 22, 1883. Term of patent 3½ years.

To all whom it may concern:

Be it known that I, PAUL PIGNOT, of Yonkers, Westchester county, State of New York, have invented a new and original Design for 5 Carpets, of which the following is a specification.

The accompanying photograph illustrates my new design for carpets.

This invention relates to a new design for 10 carpets, oil-cloths, and analogous fabrics; and it consists of the new ornamentation of parts herein more fully pointed out.

The more prominent group, A, is a floral design having a background of fern-leaves, a, 15 and in front of those heavier leaves, b, and a floral spray, d. In the center of the group A are smaller flowers, e. From the group A is suspended downward, when the carpet is

matched, a spray, f, of flowers. At one side of the group A is a group, B, of flowers, of 20 which one portion is shown on the lower left-hand side and another at the upper right-hand side of the photograph, a spray, g, of this group extending near to the spray f of the group A, as shown. A lily-like plant, C, 25 appears to grow at one side of the floral group A. In the interstices of the group A are streaks, h, resembling a cascade in the background.

I claim—

The design for carpets, consisting of figures 30 A B a b d e f g h, substantially as shown.

PAUL PIGNOT.
